(57) **CLAIM**

We claim the ornamental design for a cosmetic applicator, as shown and described.

DESCRIPTION

FIG. 1 is a top, front isometric view of a cosmetic applicator. FIG. 2 is a top, rear isometric view of the cosmetic applicator of FIG. 1.

FIG. 3 is a front elevation view of the cosmetic applicator of FIG. 1.

FIG. 4 is a rear elevation view of the cosmetic applicator of FIG. 1.

FIG. 5 is a left side elevation view of the cosmetic applicator of FIG. 1.

FIG. 6 is a right side elevation view of the cosmetic applicator of FIG. 1.

FIG. 7 is a top plan view of the cosmetic applicator of FIG. 1; and,

FIG. 8 is a bottom plan view of the cosmetic applicator of FIG. 1.

1 Claim, 4 Drawing Sheets

See application file for complete search history.
